United States Patent

Des. 242,565
Patented Nov. 30, 1976

242,565

GAME CABINET

Alan Green, San Jose, Calif., assignor to
Atari, Inc.

Filed Aug. 29, 1975, Ser. No. 608,879

Term of patent 14 years

Int. Cl. D21—01

U.S. Cl. D34—5 J

FIG. 1

FIG. 2

FIG. 3

FIG. 4

FIG. 1 is a perspective view of a game cabinet embodying my new design.

FIG. 2 is a top plan view of the game cabinet shown in FIG. 1.

FIG. 3 is a front elevational view of the game cabinet shown in FIG. 1.

FIG. 4 is a right side elevational view of the game cabinet shown in FIG. 1.

The back and bottom of the game cabinet are generally planar surfaces, and the left side is a mirror image of the right side.

I claim:

The ornamental design for a game cabinet, as shown and described.
